UNITED STATES PATENT OFFICE.

KENNETH O. DUNCAN, OF SAN FRANCISCO, CALIFORNIA, ASSIGNOR TO THE DENVER ROCK DRILL MANUFACTURING COMPANY, OF DENVER, COLORADO, A CORPORATION OF DELAWARE.

SCREEN FOR ROCK DRILLS.

Application filed April 14, 1920. Serial No. 373,832.

To all whom it may concern:

Be it known that I, KENNETH O. DUNCAN, a citizen of the United States, residing at San Francisco, in the county of San Francisco and State of California, have invented certain new and useful Improvements in Screens for Rock Drills, of which the following is a specification.

The present invention relates more particularly to drilling apparatus of the type in which the exhaust from the mechanism or a part thereof is utilized for cleansing the drill hole. In this type of apparatus, dirt and grit may find its way through the ports into the mechanism, thereby causing excessive wear and deterioration.

The object of the present invention is to provide novel and effective means for preventing the material entering the working parts through the means that directs the cleansing fluid to the bore of the drill steel.

In the accompanying drawings:—

Figure 1 is a longitudinal section through the front portion of a drilling machine, and showing the novel means in place.

Figure 2 is a sectional view on the line 2—2 of Figure 1.

Figure 3 is a detail sectional view on the line 3—3 of Figure 2.

Figure 4 is a detail cross sectional view.

Figure 5 is a perspective view of the head member carrying the screen.

Figure 6 is a detail perspective view of the screen.

Similar reference numerals designate corresponding parts in all the figures of the drawings.

In the embodiment illustrated, a drill actuating motor is employed, which may be of the well known type, and includes a cylinder, a portion of which is illustrated at 6, said cylinder containing a reciprocating hammer piston 7. The front end of the cylinder 6 is provided with an integral head portion 8 in the form of a sleeve on which is fitted a collar 9 carrying a rotary motor. This motor includes a casing or cylinder member 10 in which is the rotary piston mechanism 11. Motive fluid is supplied to the rotary motor through a suitable passage-way 12.

The front head of the rotary motor cylinder 10 is in the form of a collar 13 having a wall 14 through which extends an exhaust

port 15 for the rotary motor. The collar 13 surrounds the front end of the cylinder head 8, and is interposed between the cylinder 10 of the rotary motor and an element 16. The parts 13 and 16 together constitute a chuck head and gear case, the part 16 having journaled therein a rotary chuck 17. This chuck has at its rear end a gear 18 meshing with gearing 19 that is connected to and driven by the piston 11 of the rotary motor. The gearing, it will be noted, is housed within the parts 13 and 16. The chuck 17 is adapted to receive the rear end of a suitable drill steel 20 having a bore 21 through which cleansing fluid is passed to the bottom of the drill hole. The collar 13 is provided with a port 22 that opens into a chamber 23 formed between the front end of the piston 7 and the rear end of the chuck 17, the said collar being furthermore provided on opposite sides of the port 22 with sockets 24 that are open-ended, as illustrated in Figures 3 and 5. This port 22 allows the fluid exhausted into the gear case through the port 15, to pass into the chamber 23, and thus find access to the bore 21 of the drill steel.

In order to prevent dirt and cuttings which may enter the chamber 23, from passing into the gear case, a screen 25 extends across the port 22. This screen has terminal beads 26 preferably formed by wrapping the margins of the screen around core rods 27. The beads detachably fit in the sockets 24 and thus effectively hold the screen across the port.

From the foregoing, it is thought that the construction, operation and many advantages of the herein described invention, will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. The combination, in drilling apparatus, of a drilling motor, a chuck head on the front end thereof having an internal port and sockets formed directly in the walls on opposite sides of the same, a chuck

in the chuck head, and a screen extending across the port and having terminal portions engaged in the sockets.

2. The combination, in drilling apparatus, of a drilling motor, a chuck head on the front end thereof, comprising separable sections, one of which is provided with a cleansing fluid supply port and open ended sockets formed directly in the walls of the sections on opposite sides of the port, and a screen extending across the port and having its ends engaged in the sockets.

3. The combination, in drilling apparatus, of a drill actuating motor, a rotary motor mounted on one side of the same, a chuck head and gear case comprising separable sections, one of which has a port, and sockets formed directly in the walls thereof on opposite sides of the port, a rotatable chuck in the chuck head, a gearing connecting the rotary motor and chuck, and a screen across the port having terminal portions engaged in the sockets.

4. The combination in drilling apparatus, of a drilling motor, a chuck head on the front end thereof including a gear case,

said case comprising detachably associated sections, one of which has a motor surrounding collar and a gear enclosing portion, with a port between the two and sockets 30 on opposite sides of said port, a screen extending across the port and having its margins located in the sockets, and a rotatable tool-receiving chuck mounted in the chuck head in advance of the screen.

5. The combination in drilling apparatus, of a drill chuck rotating motor, a drill chuck geared thereto and rotated thereby, a casing enclosing the gearing and having an exhaust port opening from the motor and adapted to supply fluid to a steel placed in the chuck, said casing having sockets on opposite sides of the port, and a screen having terminal beads engaged in the sockets, said beads being formed by cores and the margins of the screen encircling said cores.

In testimony whereof, I affix my signature in the presence of two witnesses.

KENNETH O. DUNCAN.
